UNITED STATES PATENT OFFICE.

JOSEPH W. SOMMER, OF PEORIA, ILLINOIS.

WIRE FENCING.

SPECIFICATION forming part of Letters Patent No. 756,540, dated April 5, 1904.

Application filed August 28, 1903. Serial No. 171,108. (No model.)

To all whom it may concern:

Be it known that I, JOSEPH W. SOMMER, a citizen of the United States, residing at Peoria, in the county of Peoria and State of Illinois, have invented certain new and useful Improvements in Wire Fencing; and I do hereby declare that the following is a full, clear, and exact description of the invention, which will enable others skilled in the art to which 5 it appertains to make and use the same.

This invention has reference to wire fencing, and relates particularly to a fencing consisting of longitudinal strands of wire tied together in pairs by transverse strands or stays 15 that are wound or coiled at their ends about two of the longitudinal strands, the stays being arranged in break-joint fashion.

A further object of the invention is to coil the ends of the short sections of stays wrapped 20 around the same strands in the same longitudinal direction, which presents a fencing with stays in break-joint fashion having the ends of the stay-sections coiled around alternate strands over and under.

That the invention may be more fully understood reference is had to the accompanying drawings, in which—

Figure 1 shows a side elevation of a section of a fence embodying my improvements. 30 Fig. 2 is a plan or edge view of such fencing. Fig. 3 shows somewhat enlarged opposite views of a stay-section and the manner of coiling its ends around adjacent strand-wires. Fig. 4 shows a side view of parts seen in Fig. 35 Fig. 5 is an elevation in section as the coil would appear on the line X X, Fig. 4.

In the drawings, 1 and 2 designate a series of horizontal parallel strand-wires, the former numeral denoting the top and bottom wires 40 and the latter the intermediate strands. It is adapted to construct the fencing to have graduated or variable meshes; but this is not absolutely necessary, as the strands may be spaced uniformly apart, if desired.

35 3 denotes short sections of stays which appear in the fencing (see Fig. 1) in break-joint fashion or offset and have their opposite ends coiled around adjacent strand-wires at 4 to form a hinge-joint, which prevents the fence 50 being sprung permanently out of shape by

stock running against the same. The opposite ends of each stay-section are coiled around adjacent strands with the free ends of its coil directed toward its opposite coil or in opposite directions. The coils of the stay-sections 55 are wrapped closely to the body of the strand, with the free end of the coil bearing against the strand, as seen in the figures. Reference is had to Fig. 1, where the coils of the ends of adjacent stay-sections with the same horizontal strand are directed in the same direction around the strand, being over or under, which presents a fence where the coils of the stay-sections, with alternate strands, appear in opposite directions over and under, with the coils 60 of each stay-section being directed in the same longitudinal direction on each strand. The arrows shown on the second and third strand-wires, Fig. 1, illustrate the alternate over and under coil, as described. 70

Heretofore in fencing of this character the alternate coils of the stay-sections with the same horizontal strand-wires have been in opposite directions. I have done away with this form of coiling the stay-sections by the method 75 employed in carrying the strand-wires and feeding the stay-sections thereto. The strand-wires are fed through coilers, each alternate coiler of the series rotating in an opposite direction. The sections of a break-jointed stay, 80 or those sections of a stay spanning the alternate spaces between the strands in a vertical line, are fed simultaneously and alternately with those in the next vertical line, which brings the ends of adjacent stay-sections to 85 be actuated successively by the same coilers and directs all such coils around the same strand-wires in the same direction over or under.

The strand-wires are corrugated sidewise, 90 as at 5, which is better than corrugating them vertically, the latter method giving the fence an irregular appearance and making some of the meshes larger than the spacings call for, the corrugations in the wires of the fence providing for the necessary contraction and expansion of the fence. 95

Employing the stay-sections, as I do, to produce a coil moving in the same direction when they connect with the same strand-wire en- 100

ables me to produce a fence at a much greater speed than has heretofore been accomplished with similar types of stays and making it possible to manufacture the same more cheaply.

5 Having thus fully described my invention, what I claim, and desire to secure by Letters Patent of the United States, is—

10 The herein-described wire fencing, comprising a series of parallel strand-wires and a plurality of short sectional stay-wires connected with adjacent strands in break-joint fashion, the ends of succeeding stay-sections coiled

around coinciding strands in the same direction, while the coils of the opposite ends of such stay-sections with adjoining strands are 15 in an opposite direction but uniformly in the same direction with all the coils on such adjoining strands, substantially as specified.

In testimony whereof I affix my signature in presence of two witnesses.

JOSEPH W. SOMMER.
